(57) **CLAIM**

The ornamental design for a shower pan, as shown and described.

DESCRIPTION

FIG. 1 is a top plan view showing a first embodiment of the new design. The bottom of the article is flat and devoid of surface ornamentation, and is therefore not shown.

FIG. 2 is a top left perspective view thereof.

FIG. 3 is an enlarged fragmentary view of a portion of the design. The double lines surrounding the drain gate and defining the opening in the floor shown in the enlargement of FIG. 3 do not appear in FIGS. 1 and 2.

FIG. 4 is a top plan view showing a second embodiment of the new design. The bottom of the article is flat and devoid of surface ornamentation, and is therefore not shown.

FIG. 5 is a top left perspective view thereof; and, FIG. 6 is an enlarged fragmentary view of a portion of the design. The double object lines surrounding the drain gate and defining the opening in the floor shown in the enlargement of FIG. 6 do not appear in FIGS. 4 and 5.

The front, back, left and right-side elevational views of the article are flat and devoid of surface ornamentation, and are therefore not shown.

The broken lines shown in the drawings represent unclaimed portions of the shower pan and form no part of the claimed design.
